FAREBOX

Eugene Murdock Macdonald, Shaker Heights,
Ohio

Application August 27, 1936, Serial No. 98,225

5 Claims. (Cl. 232—15)

The present invention relates to a novel and improved farebox construction for the receipt and deposit of coins, fares, and the like, on peripatetic vehicles such as trolleys, trains and busses. The general object and nature of my invention is to provide a farebox of a construction adapted to better protect the contents of the farebox against tampering, theft, pilferage, or opening by unauthorized persons.

More particularly, the construction embodying my invention provides a vault normally adapted to be contained in the bottom portion of the fare box and to receive the fares and coins deposited therein. Such vault possesses a receiving opening and a door for closing such opening, together with means for automatically closing and locking the door when the vault is removed from the farebox. The invention also provides means for holding the door in open position when the vault is inserted into the farebox.

A further object of the invention is to provide a "tell tale" or indicating means visible from the exterior of the farebox which is capable of immediately informing an inspector, collector, or similar authorized person whether an attempt has been made to extract the contents of the farebox by a coin extracting instrument or "fishing tool". Additional objects and advantages of the invention shall become apparent as the following description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of the various mechanical forms in which the principle of the invention may be used.

In said annexed drawings:

Fig. 1 is an elevational view, partially broken away, of my improved farebox construction; Fig. 2 is a view taken upon a plane normal to that of Fig. 1; Fig. 3 is an enlarged sectional view of the farebox vault construction, showing the vault and its associated and cooperating parts in partially removed position with respect to the farebox; Fig. 4 is a view similar to Fig. 3 but showing the farebox vault in normal position when fully inserted in the farebox; Fig. 5 is an enlarged sectional view, taken substantially along line 5—5 of Fig. 3; Fig. 6 is a view similar to Fig. 5 but showing the parts in a different position and corresponding to that of the parts as

shown in Fig. 4; Fig. 7 is an enlarged sectional view taken substantially along line 7—7 of Fig. 4 and showing the locking elements of the vault door when the latter is in closed position; Fig. 8 is a view similar to that of Fig. 7 but showing the locking elements of the vault door when the latter is in open position; Fig. 9 is an enlarged elevational view of the mechanism positioned on the interior wall of the farebox housing, which cooperates with the vault door opening and closing mechanism; Fig. 10 is an enlarged view of the construction of the tell tale plate; and Fig. 11 is a sectional view taken upon a plane normal to that of Fig. 10.

Now referring more particularly to the drawings, my farebox consists generally, as shown in Figs. 1 and 2, of a housing 1, with a fare or coin receiving opening 2 at its top end with the removable vault 3 positioned in its bottom. A handle 4 is provided on the front end of the vault 3. A door 5 is mounted upon the hinge 6 to the housing, which closes the opening in the bottom of the farebox through which the vault 3 is removed and inserted.

Now directing attention to Figs. 3 to 6 inclusive, the vault 3 is in the form of a rectangular shaped box and has the casting 7 having the fare receiving opening 8, constituting its top wall. A sliding door 9 is mounted underneath the casting 7 and is adapted to close the opening 8 when in closed position, as best shown in Figs. 3, 5, and 8. The bottom side of the door 9 contacts with and is movable over the bearing plate 10 which is mounted to the side walls of the vault 3 by means of rivets or other suitable fasteners through the boss 11. The cylinder lock housing 12 constitutes an integral part of the bearing plate 10 and encloses the cylinder lock 13 and its appurtenant parts.

A longitudinal channel or slot 14 is provided in the medial portion of the door 9. An elongated abutment 15 is carried by the top casting 7 and extends into the slot 14. The end of the abutment 15 is wedge-shaped as indicated at 16. A pair of transversely extending slots 17 are provided in the door 9 for the reception of the bars 18 whose inner ends 20 are beveled in order to substantially fit and contact with the wedge shaped end 16 of the abutment 15. The outer ends 21 of the bars 18 are of curved form in order to produce an inward movement of the bars 18 with respect to the door 9 when the former come in contact against the teeth 22 of the gears 23. Slots 19 are provided in the walls of the vault 3 for passage of the bars 18.

As best indicated in Fig. 9, the gears 23 are mounted upon stub shafts 24 in turn carried by the plates 25. Each one of the plates 25 is fastened to the inner side walls of the housing 1 of the farebox. A pawl 26, pivotally mounted upon the pin 26' engages with the teeth 22 of the gear 23 and prevents rotation of the latter in a direction opposite to that indicated by the curved arrow in Fig. 9. The curved arrow and the straight arrow in Fig. 9 correspond to the direction of inward movement of the vault 3 when it is inserted into the farebox housing 1. A round headed pin 27 is spring loaded by the compression spring 28 carried in the channel 29 and bears against the intermediate portion of the pawl 26 in order to retain the latter in operable position.

The gear 23 meshes with a second gear 30 mounted upon the stub shaft 31. A gravity operated pawl 32, pivoted upon the pin 33 bears against the teeth of the gear 30 as indicated at 34. The second gear 30 together with its pawl 32 serves as a safety device in the event that the pawl 26 should become inoperative through sticking, or breaking of the spring 28. Furthermore, the action of the spring 28, the pawl 26, the gear 30 and the weighted pawl 32 operate as means for imparting a slight resistance to the rotation of the gear 23 in the direction of the curved arrow in Fig. 9.

The last described mechanism constitutes means for automatically closing the vault door 9 on its withdrawal from the farebox housing 1 and for simultaneously and automatically preventing the complete withdrawal of the vault 3 until the door 9 is completely closed. The operation of this mechanism is as follows: Referring first to Figs. 4 and 6, the door 9 will be seen to be in open position whereby the opening 8 in the top casting 7 is in communication with the interior of the vault 3. In this position, the bars 18 are held in a laterally projecting position beyond each side of the vault 3, with their ends 21 extending out through the slots 19. As the vault 3 is moved outwardly from the farebox housing, i. e., in a left hand direction with respect to Figs. 3 to 6 inclusive, the bars 18, bearing against the gear teeth 22 of the gears 23 (which latter are locked against rotation in the direction which the bars 18 tend to move then on outward movement of the vault 3) carry the door 9 to closed position, and not until the door 9 reaches such closed position do the inner ends 20 of the bars 18 reach the end 16 of the abutment 15. At this point the bars 18 are permitted to retract inwardly from the slots 19 in the side walls of the vault 3 and their outer ends 21 thereby to clear the gear teeth 22 so that the vault 3 can be completely withdrawn from the farebox housing 1.

Conversely, it should be readily understood that when the vault 3 is inserted into the farebox housing 1, the vault having its door 9 in open position, with the ends 21 of the bars 18 projecting laterally, that the bars 18 will bear against the teeth 22 substantially in the manner shown by the straight arrow in Fig. 9 and that the slight resistance to rotation of the gear 23 will hold the door 9 in open position as the vault 3 is inserted into the farebox housing 1. Thus any tendency of the door 9 to slightly close upon the inserting movement of the vault 3, would be prevented.

75 It should be noted that slots 35 are provided

in the plates 25 for the passage of the ends of the bars 18.

The under side portion 40 of the door 9 is spaced from the upper wall thereof and provides a space 41 in which a pair of latch members 42 are pivotally mounted as at 43. A pair of round headed, spring loaded pins 44 bear against the free ends of the latch members 42 and tend to force the latter into a converging position. The cylinder lock 13 has a stem 45 connected to the rotatable shaft 46. A striker member 47 is mounted upon the end of the shaft 46 and is adapted to be engaged by the notches 48 in the latch members 42 and by the outer ends of the latch members 42, the latter engagement being best shown in Fig. 7. An L-shaped opening 49 is provided in the bottom wall portion 40 of the door 9 in order to permit the passage of the door 9 with respect to the striker member 47, and also to permit rotation of the striker member 47 to inoperative position as shown in Fig. 4.

As the door 9 is moved from open position as shown in Fig. 8 to closed position as shown in Fig. 7, the latch members 42 bear against the striker member 47. The notches 48 in the latch members 42 contact and engage with the striker member 47 thus preventing any attempt at again moving the door 9 toward open position, once the latter has been moved to partially closed position. When the door 9 occupies fully closed position as shown in Fig. 7, the ends of the latch members 42 are forced by the spring loaded pins 44 to abut against the side of the striker member 47 and thereby prevent any further opening of the door 9 until an authorized person operates the cylinder lock 13 and thereby rotates the striker member 47 to unlocked position where it clears the ends of the latch members 42 and permits the door 9 to be opened with the fingers.

Referring back to Figs. 1 and 2, and also to Figs. 10 and 11, substantially the upper half portion of the farebox housing 1 constitutes a fare receiving passage whose walls 50 are composed of glass so that the interior of such passage is visible from outside the farebox. Baffle plates 51 and 52 are mounted in angularly inclined positions from the vertical in the interior of the fare receiving passage defined by the walls 50. A tell tale plate 53 is mounted upon the under side of the baffle 51 and projects slightly beyond the lower end thereof. The projecting end of the plate 53 is serrated as indicated at 54. The plate 53 is pivotally mounted by means of the hinge 55, to the U-shaped rod 56. The legs 57 of the rod 56 are slidably mounted in the guides 58 which in turn are secured to the under side of the baffle plate 51. The outer ends of the legs 57 are laterally bent as indicated at 59 in order to limit the downward movement of the bar 56 with respect to the baffle plate 51.

The tell tale plate 53 has an opening 60 which is larger than the head of the headed pin 61. The headed pin 61 is mounted upon the baffle plate 51 and extends through the opening 60 and engages with its edge in order to normally retain the tell tale plate in the position shown in full lines in Figs. 2 and 11.

When pilferage or theft of the contents of the farebox might be attempted by inserting a coin or fare extracting instrument, or "fishing tool" through the opening 2, such instrument must necessarily come in contact with the serrated edge 54 of the tell tale plate 53. Then as such instrument is withdrawn, the tell tale plate will be slid upwardly along the under side of the baffle 51

plate 51 until the headed pin 61 clears the edge of the hole 60. As the plate 53 reaches such position, it will be permitted to hang in a vertical position as shown by the dotted lines in Figs. 5 2 and 11. In this manner, attempted theft or tampering with the contents of the farebox will be immediately indicated to authorized persons upon inspection, and an appropriate investigation may then be instituted.

10 Practically any type of coin extracting instrument will operate the tell tale plate 53. Such instruments usually consist of a flexible metal strip with a gripping tongue or a piece of chewing gum on the end, or a string with a magnet or 15 grasshopper tied to the end. Such instruments must necessarily contact with the projected edge of the tell tale plate 53, and once they are started on their withdrawing movement from the farebox (which is necessarily the case in the operation of such instruments), the plate 53 will 20 be tripped to a vertically hanging position.

Other modes of applying the principle of my invention may be employed instead of the one explained, change being made as regards the 25 mechanism herein disclosed, provided the means stated by any of the following claims or the equivalent of such stated means be employed.

I therefore particularly point out and distinctly claim as my invention:

30 1. In a farebox, the combination of a removable vault adapted to be inserted into and then withdrawn from the base of said farebox, a slideable door in the top of said vault, transversely extending slots in said door, bars longitudinally movable in said slots, an abutment carried by said vault and adapted to be engaged by the ends of 35 said bars on opening movement of said door whereby said bars are moved outwardly of said vault, and means positioned interiorly of said 40 farebox for engaging with the outer ends of said bars.

2. In a farebox, the combination of a removable vault adapted to be inserted into and then withdrawn from the base of said farebox, a slideable door in the top of said vault, transversely extending slots in said door, bars longitudinally movable in said slots, an abutment carried by 45 said vault and adapted to be engaged by the ends of said bars on opening movement of said door whereby said bars are moved outwardly of said vault, and pawl and ratchet means positioned in 50 the interior of said farebox and adapted to be engaged by the outer ends of said bars to permit

their passage on inward movement of said vault with respect to said farebox, and to prevent their passage on outward movement of said vault.

3. In a farebox, the combination of a removable vault adapted to be inserted into and then withdrawn from the base of said farebox, a slideable door in the top of said vault, transversely extending slots in said door, bars longitudinally movable in said slots, an abutment carried by said vault and adapted to be engaged by the ends of 10 said bars on opening movement of said door whereby said bars are moved outwardly of said vault, gears mounted on the interior of said farebox having teeth adapted to be engaged by the outer ends of said bars, and pawls engaging said 15 gears whereby the latter are rotatable only in a direction corresponding to the inward movement of said bars and of said vault with respect to said farebox.

4. In a farebox the combination of a removable 20 vault adapted to be inserted into and withdrawn from the base of said farebox, a door slideable in the top of said vault, means for automatically closing said door when said vault is removed from said farebox, a key operated lock mounted in said 25 vault, a rotatable striker member connected to and operable through said lock, and a pair of pivoted latch members carried by said door and adapted to engage with said striker member when said door is moved to closed position, said striker 30 member being rotatable to a position clear of said latch members, whereby said door is movable to open position.

5. In a farebox the combination of a removable 35 vault adapted to be inserted into and withdrawn from the base of said farebox, a door slideable in the top of said vault, means for automatically closing said door when said vault is removed from said farebox, a key operated lock mounted in said vault, a rotatable striker member connected to 40 and operable through said lock, a pair of pivoted latch members carried by said door and adapted to engage with said striker member when said door is moved to closed position, said striker member being rotatable to a position clear of said 45 latch members, whereby said door is movable to open position, and a plurality of notches in said latch members, said notches being adapted to engage with said striker member and to lock said door against opening movement when the latter 50 approaches closed position.

EUGENE MURDOCK MACDONALD.
